UNITED STATES PATENT OFFICE.

JOHN W. TAYLOR, OF REEDSVILLE, AND WILLIAM J. HUNTER, OF HUNTINGDON, PENNSYLVANIA.

HARVESTING-MACHINE.

SPECIFICATION forming part of Letters Patent No. 740,947, dated October 6, 1903.

Application filed April 20, 1903. Serial No. 153,387. (No model.)

To all whom it may concern:

Be it known that we, JOHN W. TAYLOR, of Reedsville, Mifflin county, and WILLIAM J. HUNTER, of Huntingdon, Huntingdon county, 5 Pennsylvania, citizens of the United States, have invented certain new and useful Improvements in Harvesting-Machines, of which the following is a specification.

This invention relates to harvesting-machines; and the object thereof is to provide simple and effective means for preventing the grain from choking at the juncture of the elevators and deck-board. A slight space necessarily occurs at this point to provide for 15 free operation of the lower elevator, and as this space is directly beneath where the elevators discharge the tendency of the grain to catch therein and choke or clog is considerable, and especially so when it is short or 20 tangled. We propose to obviate this difficulty by providing a bridge or guard for closing said space, having yielding engagement with the lower elevator. By this means the 25 tendency to choke is obviated and any grain that may become lodged at said point is readily worked down by and discharged beneath the lower elevator.

In the accompanying drawings, Figure 1 is a detail perspective view of the elevators and 30 a portion of the deck-board with our improvement in position. Fig. 2 is a vertical sectional view. Fig. 3 is a view similar to Fig. 2, showing a modification.

Referring to the drawings, 2 designates the 35 deck-board, 3 and 4 the upper and lower elevators, and 5 the elevator-slats. To assure the lower elevator free and uninterrupted operation, a slight space occurs between the same and the upper edge of the deck-board. 40 To close this space, we provide a bridge or guard 6, which is preferably so curved or shaped that its lower portion 6' parallels the under surface of the lower elevator 4 and is adapted to bear thereagainst. The bridge or 45 guard may be supported in any suitable manner. In Figs. 1 and 2 the upper edge thereof is shown overlapping and secured to the upper face of the deck-board, while in Fig. 3 it is shown hinged at 7 to the edge of the 50 deck-board. Springs 8 are shown secured to the under side of the deck-board at 9, which

bear against portion 6' of the guard and hold the same against the canvas with a yielding pressure. If formed of spring metal and rigidly secured, as in Figs. 1 and 2, the guard 55 may be sufficiently resilient to exert the requisite pressure without the springs, in which event the latter may be dispensed with. It will be understood, however, that the guard may be supported and caused to exert yielding pressure on the elevator in a variety of ways without departing from the spirit of our invention. Obviously it may be constructed of any suitable material.

With the bridge or guard arranged as shown 65 its tendency is to deflect the grain down over the deck-board as it discharges from the elevators. If, however, any portion thereof lodges on the guard, it is drawn downward thereover and discharged by the slats 5 of the 70 lower elevator, which scrape downward over portion 6' of the guard as they descend. Thus simple and effective means is provided for facilitating passage of the grain from the elevators to the deck-board and for preventing 75 choking at the juncture of said parts.

We claim as our invention—

1. In a harvesting-machine, the combination with the elevators and deck-board, of a bridge or guard closing the space intermediate said parts and having a yielding portion extending beneath the lower elevator, substantially as described.

2. In a harvesting-machine, the combination with the elevators and deck-board, of a bridge or guard closing the space intermediate said parts and having a free portion extending beneath the lower elevator, and means for yieldingly holding said free portion of the bridge in close proximity to the lower elevator, substantially as described.

3. In a harvesting-machine, the combination with the elevators and deck-board, of a bridge or guard closing the space intermediate said parts and extending beneath and adjacent the under side of the lower elevator, and means for causing the depending portion of the guard to bear against said elevator, substantially as described.

4. In a harvesting-machine, the combination with the elevators and deck-board, of a bridge or guard closing the space intermediate

ate said parts and secured to the deck-board with its free portion extending beneath the lower elevator, and means for causing said depending part to bear against the elevator, 5 substantially as described.

5. In a harvesting-machine, the combination with the elevators and deck-board, of a bridge or guard secured to the deck-board and closing the space between the same and 10 the elevators, the outer portion of the guard extending beneath the lower elevator, and springs for holding the guard against the elevator, substantially as described.

6. In a harvesting-machine, the combination with the elevators and deck-board, of a bridge or guard closing the space intermediate said parts and having yielding engagement with the lower elevator, substantially as described.

In testimony whereof we affix our signatures in the presence of two witnesses.

JOHN W. TAYLOR.
WILLIAM J. HUNTER.
